UNITED STATES PATENT OFFICE.

VIRGIL L. DU BOIS AND CLARENCE E. CLIFTON, OF TULSA, OKLAHOMA.

COMBINED BABBITTING AND FINISHING JIG.

Application filed November 6, 1923. Serial No. 673,169.

To all whom it may concern:

Be it known that we, VIRGIL L. DU BOIS and CLARENCE E. CLIFTON, citizens of the United States, and residents of Tulsa, county of Tulsa, and State of Oklahoma, have invented certain new and useful Improvements in Combined Babbittting and Finishing Jigs, of which the following is a full and complete specification, reference being had therein to the appended drawings.

This invention relates to the babbittting and finishing of the bearings for crank shaft journals as found in gas engines, pumps, compressors and the like. In devices of this character it is essential that the bearings be relined with Babbitt metal from time to time. It is also necessary that the new bearings be finished by boring. As these bearings are generally at least three in number, great care must be exercised to insure the proper alignment of the same.

It is an object of this invention to develop a device capable of use in both the babbitt casting step and the subsequent step of boring out the cast bearings.

It is also an object of this invention to simplify the device required to carry out the above two steps and to insure the uniformity and accuracy of the work done.

Other advantages resulting from our invention will be apparent from the following description of one form, in which:

Figure 1 is a plan view of the jig used in the babbittting step;

Fig. 2 is a plan view showing the same in the operation of boring out the cast bearings;

Fig. 3 is a detail perspective view during babbittting, and

Fig. 4 is a side view of the locking nuts.

As illustrating one preferred form of our invention, there has been shown in the drawings a frame or spider 5, conforming in general to the shape of the cylinder block 6 or an analogous casting of the crank case of a gas engine, pump, compressor or the like. This frame 5 is provided with a series of pins 7, passing through the sides of the frame 5 and projecting into the customary bolt holes found in the walls of the member 6. By means of the pins 7, the jig may be clamped readily to the machine part which it is desired to supply with new bearings.

A plurality of yokes or cross arms 8, 8 55 extend between the sides of the jig 5 and form bearings 9, 9.

The member 6 is shown to have an intermediate transverse partition 10 and end walls 11 and 12. The partition and end 60 walls each carry journal boxes 13.

Journalled in the bearings 9 of the jig 5, and passing through the journal boxes 13 is a bar 14, which serves the purpose of forming cores during the babbittting step 65 and as a boring bar during the finishing step.

Throughout the greater part of its length, the boring bar 14 has a uniform cylindrical surface as shown at 15, 16 and 17. These 70 uniform cylindrical portions are so disposed as to occupy the journal boxes 13 when the bar is at its limiting position shown in Fig. 1.

Suitably spaced along the bar 14 and between the portions 15, 16 and 17 are recessed portions 18 and 19. A recessed portion 20 is adjacent the portion 17. The recessed portions 18, 19 and 20 are so spaced as to be brought opposite the journal boxes 13 80 simultaneously.

Each of the recessed portions 18, 19 and 20 carry boring tools 21.

The boring tool 14 is provided at one end with a handle 22 by which the boring bar 85 may be rotated in the bearings 9. A screw-thread 23 is formed on the boring bar 14 as shown in the drawings, and constitutes the means for advancing the boring bar with respect to the work.

The jig 5 has at one end converging arms 24, 24 carrying at their ends internally screw-threaded blocks 25, 25, by means of pivot pins 26, 26. The blocks 25, 25 are of such shape as to completely surround 95 screw-thread 23 and are conical as shown. The outer cylindrical surface of the blocks 25, 25 is screw-threaded to receive the locking nut 27.

In Fig. 3 is shown a detail of the boring 100 bar in the position for forming a core in the journal box 13 during the babbittting step. Mold members 28, 28 of semi-circular form are adapted to be held tightly on the boring bar 14 by means of clamping springs 105 29, 29 in the manner shown.

Where it is desired to cast the babbittting metal in the journal boxes 13, the jig 5 is

placed upon the member 6 with the pins 7 registering in the bolt holes of member 6. With the blocks 25, 25 released, the boring bar 14 is moved in bearings 9 to the 5 position shown in Fig. 1. This brings the cylindrical portions 15, 16 and 17 opposite journal boxes 13. The blocks 25, 25 are then closed around screw-thread 23 and the locking nut 27 fastened on the blocks in order to 10 hold the boring bar stationary.

The mold members 28, 28 are then slid 15 along a boring bar or clamp around the same forming molds of the desired shape in the partition 10 and the end walls 11 and 12. The babbitt metal is then poured into the 20 molds and the device allowed to remain in this position until the babbitt metal has solidified.

After the new bearings have been cast, the 25 mold members 28, 28 are removed and surplus babbitt metal cleared away. The crank handle 22 is then rotated. As the handle is rotated the feed screw 23 is forced along the blocks 25 and consequently causes 30 the boring tools 21 to pass along the inner surface of the bearings. In this way the bearings are bored out, the borings being removed along the relieved or recessed portions 18, 19 and 20.

In this manner the jig serves the purpose 35 of establishing properly aligned cores in the journal boxes during the casting step as well as rapidly and effectively boring out the bearings in the finishing step.

While we have shown by way of example 40 one form in which our invention may be embodied, numerous changes may be made without departing from the scope of the invention as defined in the appended claims.

What we claim as our invention is:

1. A combined babbittting and finishing 45 jig consisting of a frame, bearings in said frame and a combined core member and boring bar movable longitudinally in said bearings.

2. A combined babbittting and finishing 50 jig consisting of a frame, bearings in said

frame, a combined core member and boring bar movable longitudinally in said bearings, 55 said bar having spaced reduced portions and cutting members carried in said portions.

3. A combined babbittting and finishing jig 60 consisting of a frame, bearings in said frame and a boring bar movable longitudinally in said bearings, said bar having portions 65 adapted to serve as cores during the casting of the Babbitt metal.

4. A combined babbittting and finishing 65 jig consisting of a frame, bearings in said frame, a boring bar movable longitudinally 70 in said bearings, said bar having portions adapted to serve as cores during the casting of the Babbitt metal and mold members removably carried by said bar.

5. A combined babbittting and finishing 75 jig for shaft bearings consisting of a frame, means on said frame for registering the same in desired position with respect to the 80 bearings to be constructed, bearings in said frame, a combined core member and boring bar in said frame bearings and means to control the longitudinal movement of the bar in said frame bearings.

6. A combined babbittting and finishing 85 jig consisting of a frame having a plurality of cross members, bearings in said members, a split collar pivotally carried by said frame in alignment with said bearings, said collar being internally screw-threaded, a locking nut for the collar and a combined 90 core member and boring bar journaled in said bearings and engaged by said collar.

7. A combined babbittting and finishing 95 jig consisting of a frame having a plurality of cross members, bearings in said members, a combined core member and boring bar in said bearings, cutting members mounted on said bar and means to advance said bar and members through said bearings.

In testimony whereof, we have hereunto 90 affixed our signatures.

VIRGIL L. DU BOIS.
CLARENCE E. CLIFTON.
